BINDER

John D. Schneider, Deerfield, and John L. Nolan, Glenview, Ill., assignors to Hollister, Inc., a corporation of Illinois

Filed Dec. 13, 1962, Ser. No. 246,288
5 Claims. (Cl. 129—24)

This invention relates to ring holders for holding papers and the like. More particularly, this invention relates to ring holders of the loose-leaf type having aligned ring halves capable of opening and closing for insertion and removal of papers from the ring holder.

Loose-leaf type ring holders are used in many places, such as for example, in hospitals for keeping records. As sheets become full, new sheets are added leaving the hold sheets in the binder. Difficulty is often experienced in adding new sheets because binders have been conventionally either difficult to open or too easy to close. Too easy closing of the binder can result in injury to a person carelessly closing the rings in that the ring parts are usually sharp and the spring is often powerful; or the ring can accidentally snap shut causing severe cutting of flesh. Obviously, these conditions are undesirable.

Further, conventional loose-leaf type ring holders are usually clipped with a metal ring carrier which is wider than the ring. Such wide ring carrier inhibits the turning of leaves or sheets within the ring holder back on themselves for writing on the reverse side. The sheets normally must bend around the back of the ring carrier and the tendency is for such leaves to tear out of the rings.

It is a general object of this invention to provide a new and useful holder which overcomes the problems mentioned above as well as many others.

Another object is to provide a ring holder which is spring urged to the closed position and lockable in either the open or closed position.

It is a further object of this invention to provide such a ring holder in which a set of one or more ring halves is secured to each of two bars which can be pivoted longitudinally with respect to each other along a longitudinal axis or fulcrum, the ring halves cooperating to form rings which can be opened or closed, and in which a part of each bar comprises a joining member which is adapted to be received by a similar member on the other bar to lock the ring holder in both open and closed positions.

An additional object of this invention is to provide such a ring holder in which longitudinally slidable bars are urged by compression of the spring means acting along the bars to slide longitudinally with respect to each other for engagement of locking means with the ring holder in either open or closed position.

Still another object of this invention is to provide a ring holder device for holding papers and the like including tube means enclosing the pivotal axis of the pivotable ring halves and a coil spring means within the tube for the purpose of urging the ring halves toward their closed position.

Another object is to provide such a ring holder device with gripping or handle means for disengaging the locking means and, in one aspect, also to provide such gripping or handle means which projects sufficiently lengthwise from the ring holder device to provide for suspending the device by the handle or gripping means in a chart rack.

It is yet another object of this invention to provide a ring holder device which is constructed of first and second ring half assemblies, each assembly comprising an elongated bar having a handle end and having a

2

plurality of ring halves secured on the bar adjacent one edge of the bar and extending from a first side of the bar, each bar having an angular surface defining a fulcrum adjacent the other edge of the bar and on the second side of the bar, each bar also having a cylindrical surface opposing the fulcrum, the axis of the cylindrical surface being at the fulcrum, the ring half assemblies having their fulcrum surfaces held together in pivotal cooperation for opening and closing the ring holder device, the holding together being accomplished by a slotted cylindrical tube covering the cylindrical surfaces, having its axis at the axes of the cylindrical surfaces coinciding with the fulcrum and enclosing the spring means within the tube and within recesses within the cylindrical surface portions of the elongated bars, the spring means being capable of urging the bars on their fulcrum surfaces to a closed position with respect to the ring halves.

It is another object of this invention to provide a new and useful ring holder in accordance with any of the foregoing objects wherein the rings in closed position are of oval configuration and separable along a side of the oval, thereby providing greater width with respect to depth of the ring holder for increasing the capacity of the ring holder for holding a greater number of sheets of paper.

It is a still further object of this invention to provide a ring holder in accordance with any of the foregoing objects wherein a narrow ring carrier is included to permit more ease in turning of sheets within the holder back on themselves for writing on reverse sides without undue tearing of the sheets from the rings.

Yet a further object of this invention is to provide a new and useful ring holder in accordance with the foregoing objects which may be safely used.

Other objects of this invention will be apparent to those in the art from the following description and the drawings in which:

FIGURE 1 illustrates several units constructed in accordance with one embodiment of the ring binder of this invention suspended in a chart rack;

FIGURE 2 is a side view and partial section of the embodiment of FIGURE 1 with the rings in closed position;

FIGURE 3 is a top view of the embodiment of FIGURE 1 with slotted tube 51 removed;

FIGURE 4 is a bottom view of the embodiment of FIGURE 2;

FIGURES 5 and 6 illustrate a portion of FIGURE 2 enlarged to better show the locking means;

FIGURE 7 is a horizontal section along lines 7—7 in FIGURE 5; and

FIGURE 8 is a vertical section along line 8—8 in FIGURE 5.

With reference to FIGURE 1, ring holder devices indicated generally at 20, are shown suspended from sides of chart rack 10 by extended ends of the ring holder devices shown generally at 13 and 14. The ring holder devices contain papers, including charts and the like, relating to hospital patients.

Referring now to FIGURES 2 through 8, ring holder device 20 is constructed of two ring half assemblies. The ring half assemblies include a narrow carrier, such as plastic bars 21 and 22, with rings, such as oval rings formed from ring halves 23a through 23h and 24a through 24h secured to the lower edges of bars 21 and 22 respectively. In the illustrated embodiment each bar 21 and 22 is molded integrally with the ring halves secured thereto; however, it is to be understood that other materials of construction and other means for securing the ring halves to the bars may be used. Preferably, the rings and especially the points of the rings may be of a plastic material providing no edges capable of injuring

70

the user. Handles 25 and 26 are moded parts of bars 21 and 22 at the handle or gripping ends thereof.

Bars 21 and 22 have cylindrical surfaces 31 and 32 respectively. Fulcrum surfaces 33 and 34 are also provided on bars 21 and 22. The fulcrum surfaces are on opposite sides of the bars from cylindrical surfaces 31 and 32 but are along the same edge as the cylindrical surfaces. The fulcrum surfaces comprise a flat tapered surface along one longitudinal side and edge of each bar. Longitudinal fulcrum 35 occurs where the two fulcrum surfaces pivot with respect to each other, i.e., in the illustrated embodiment where the planes of the fulcrum surfaces intersect the planes of the inner sides of bars 21 and 22 as best shown with reference to FIGURE 8.

Each of bars 21 and 22 is provided with a pair of projections 41 on the inner side of the bar or that side of the bar which faces the other bar and pivots thereon at longitudinal fulcrum 35. Each projection 41 projects inwardly, with respect to the ring holder, and over an opening 42 provided through the bar on which the projection is secured. The projections 41 are fittable into openings 42 opposing them on the opposing bar. Thus, the projections 41 and openings 42 provide for interlocking of the projections when engaged with the bars in closed position. The engagement of projections is attained during closure of the ring halves by longitudinal and pivotal movement of the bars as may be accomplished by means of handles 25 and 26.

The projections 41 are each defined by a closed position engaging and locking surface 43 and an open position engaging and locking surface 44 and an angular surface 45 extending from adjacent the closed position locking surface to the open position locking surface. The bars and ring halves are locked in closed position by engagement of the closed position locking surfaces with each of projections 41 extending into a cooperating opening 42 and interlocking another projection 41. With the ring halves and bars in open position, each of projections 42 has its open position locking surface 44 abutting an open position locking surface 44 of another projection 41 and preventing the projection 41 from entering an opening 42.

Slotted metal tube 51, having longitudinal slot 52, surrounds the upper portions of bars 21 and 22 and contains cylindrical surfaces 31 and 32 and fulcrum surfaces 33 and 34, including longitudinal fulcrum 35, therein. Slotted tube 51 is concentric with cylindrical surfaces 31 and 32 and the center of the slotted tube coincides substantially with longitudinal fulcrum 35. Thus, the cylindrical surfaces ride substantially parallel to the inner surface of tube 51 during opening and closing of the rings. Of course, it is to be understood that precise alignment of the center of tube 51, the centers of the cylindrical surfaces 31 and 32 and the longitudinal fulcrum 35 is not necessary. Various operable modifications, including elimination of cylindrical surfaces, will be apparent to those in the art.

Tube 51 holds bars 21 and 22 in association at longitudinal fulcrum 35. Bar 21 is provided with recesses 56a, 57a, 58a and 59a and bar 22 is provided with corresponding recesses 56b, 57b, 58b and 59b. Recesses 56a and b are aligned when the bars are in the locked open position, as are recesses 57a and b, recesses 58a and b and recesses 59a and b aligned with the bars in locked open position. Contained within aligned recesses 56, 57, 58 and 59 respectively are coil springs 61, 62, 63 and 64. The coil springs are under torsion and are longitudinally compressible and preferably under some compression when bars 21 and 22 are in locked position as well as unlocked position. Ends of the coil springs project to engage bars 21 and 22 on their outer surfaces to urge bars 21 and 22 together by pivoting around longitudinal fulcrum 35. Engagement of ends 61a, 62a, 63a, and 64a of coil springs 61, 62, 63 and 64 respectively with the exterior or outer surface of bar 21 is best shown in FIGURE 2. Ends 61b, 62b, 63b and 64b

of springs 61, 62, 63 and 64 are engaged with the outer surface of bar 22, e.g. as shown for end 63b in FIGURES 5 and 6, and it is evident that like engagement is provided for the ends of the other coil springs on the outer surface of bar 22. Slight notches, e.g., as shown at 21a, 21b, 21c, 21d and 22c, are provided on the outer surfaces of bars 21 and 22 at the places where the ends of the coil springs engage the bars to prevent the ends from slipping out of engagement. Also, small notches (not shown) are provided in tube 51 at slot 52, wherever necessary, to permit projection of the spring ends from tube 51. Because bars 21 and 22 are longitudinally slidable within tube 51, tube 51 being longitudinally slidably fitted over the cylindrical surfaces of bars 21 and 22, the notches for protrusion of the spring ends from tube 51 should be sufficiently elongated to permit slidable movement of the bars with respect to each other to move the bolt ends of the bars to and from the locked position. The projections of the spring ends, in addition to compression of the springs themselves, may serve as inhibitors or stops for the sliding motion of the bars with respect to each other.

It is apparent that tube 51 contains the coil springs which are under torsion and compression within the recesses 56, 57, 58 and 59. The coil springs contained within tube 51 have their ends mounted on nubs 69 of bars 21 and 22 extending from each end into recesses 56 through 59.

In operation of the illustrated ring holder device, assuming the ring holder to be in locked, closed position, as shown in FIGURE 2, to unlock the device handles 25 and 26 are gripped and pulled outward, thereby dislodging projections 41 from each other and from slots 42. Springs 61 through 64 are thereby further compressed. Handles 25 and 26 are then pivoted away from each other along line 35. The pivoting motion causes increased torsion in springs 61 through 64. Upon pivoting bars 21 and 22 by handle 25 and 26 respectively, sufficiently to align surfaces 44 of projections 41, the outward or longitudinal pull on handles 25 and 26 is released and projections 41 are urged by compression of springs 61 through 64 toward each other with surfaces 44 engaging and/or sliding over each other to lock the rings in open position. Surfaces 45 are inclined and may engage each other upon release of handles 25 and 26, in which case the incline of surfaces 45 is such to direct projections 41 into engagement of surfaces 44 under urging of the springs.

To close the rings of the ring holder, handles 25 and 26 are pulled outwardly sufficiently to dislodge projections 41 from each other. The torsion of springs 61 through 64 then causes pivoting of bars 21 and 22 about longitudinal fulcrum 35 toward each other and toward closed position. When surfaces 43 become realigned with each other, with projections 41 within slots or openings 42, the compression of the springs urges the projections into surface to surface engagement of surfaces 43 and the ring holder is again in locked closed position.

The foregoing detailed description has been given for clearness of understanding only and no unnecessary limitation should be understood therefrom. Some modification should be obvious to those skilled in the art.

We claim:

1. A ring holder device comprising: first and second identical ring half members each comprising an elongate bar having inner and outer faces and upper and lower edges, said bars including a generally flat base portion, a plurality of ring halves extending from the lower edge of each outer face, a rocking portion near the upper edge having a generally cylindrical surface on the outer face and an inner face which flares outwardly away from the base inner face toward the upper edge, said first and second member being normally disposed with their respective base inner faces adjacent each other and with their ring halves mating to form a closed loop and define a closed ring holder position with said rocking portion inner

faces flaring away from each other; a longitudinally slotted cylindrical tube covering said cylindrical surfaces and mounting said ring half assemblies for slidable movement relative to each other as well as swingable movement wherein said cylindrical surfaces rotate relative to said cylindrical tube to bring said rocking portion inner faces toward each other and said ring halves are spread apart to define an open position; locking means on each of said assemblies, said locking means including a projection on each bar opposing a similar projection on the other bar and slidably engageable with said opposing projection when the bars are slidably moved relative to each other, engagement of said projections corresponding to said closed and fully open positions to selectively retain said ring holder in either position; and a handle portion projecting laterally outwardly from opposed ends of said members affording a surface for grasping the members and manipulating the same for slidable and swingable movement between open and closed positions.

2. The device of claim 1 including spring means within said tube urging said ring holder toward said closed position and urging said projections into slidable engagement with each other.

3. The device of claim 2 wherein said spring means is a plurality of coil springs mounted within said tubes and each of said coil springs engages the outer face of said bars so that longitudinal movement of said ring halves relative to each other is in opposition to the tension of said springs and the torsion of said springs normally urges said device to said closed position.

4. A ring holder device comprising: first and second ring half members each comprising an elongate bar having inner and outer faces and upper and lower edges, said bars including a generally flat base portion, a plurality of ring halves extending from the lower edge of the outer face of said base portion, and rocking portions on the upper edge of said base portions, said first and second members being normally disposed with their respective base inner faces adjacent each other and with their ring halves mating to form a closed loop and define a closed ring holder position; a longitudinally slotted cylindrical tube covering said rocking portions and mounting said ring half members for slidable movement relative to each other as well as swingable movement wherein said ring halves are spread apart to define an open position; and locking means on each of said members, said locking

means including a projection on each bar in general opposition to a similar projection on the other bar and slidably engageable with said opposing projection when said bars are slidably moved relative to each other, engagement of said projections corresponding to said closed and open positions to selectively retain said ring holder in either position and recesses in either bar generally opposite the projection of the other bar to receive said projections when in locking engagement in said closed position to permit said base portion inner faces to abut one another so that said ring halves may mate to form a closed loop, said projection positioned adjacent to said recesses with a portion overhanging said recesses so that when the ring holder is in the closed position, the opposing projections occupy the opposing recesses in juxtaposition with the opposing overhanging portions to prevent rotational opening movement of the ring holder, said projections having a cam surface on the overhanging portion which inclines away from the recess so that when the holder is swung to an open position, the members may be slid relative to each other to bring the cam surfaces into juxtaposition to hold the binder in a fully open position.

5. A ring holder of claim 4 including spring means within said tube for urging said ring holder toward closed position and urging said projection into slidable engagement with each other, said spring means comprising a plurality of coil springs mounted within said tubes, each of said coil springs including the outer face of said bars so that longitudinal movement of the ring halves relative to each other is in opposition to the tension of said springs and the torsion of said springs normally urges said device to said closed position.
